UNITED STATES PATENT OFFICE

EUGENE A. THOMPSON, OF SYRACUSE, NEW YORK, ASSIGNOR TO STEADFAST MANUFACTURING COMPANY, INC., OF GENEVA, NEW YORK, A CORPORATION OF NEW YORK

VENTILATOR

Application filed March 14, 1927. Serial No. 175,399.

This invention relates to a new and improved method for exhausting air from enclosed vehicles.

The main object of my invention is to provide a means whereby the air confined in an enclosed moving vehicle may be withdrawn from such vehicle without introducing into the vehicle outside air through the means of ventilation.

10 Another object is to provide a means of ventilation which will function without exposing the interior of the vehicle to the outside elements.

Other objects and advantages relate to the 15 details and form of the device, all as will more fully appear from the following description taken in connection with the accompanying drawings, in which:

Figure 1 is a perspective view showing 20 the application of my device to the window of a vehicle (in this case an automobile).

Figure 2 is a longitudinal cross-section through the device.

Figure 3 is a section at line 3—3, Figure 2.

25 Figure 4 is a perspective view partially in section showing the details of the two ends of my device.

This device can be made of any suitable metal or other material, and may be given 30 any desired finish or decoration after it has been fabricated. It may be positioned in the upper part of a window, as shown in Figure 1, being locked into place by the window glass which is raised and seated in a recess along the bottom edge of the device, or it may be permanently inset in any desired part of the vehicle body.

The device consists of the main barrel 40 —1— which is formed in an approximately half-round shape, the front end —2— being somewhat larger than the rear end —3—, the barrel tapering from front to rear so that the air passing therethrough will increase in velocity as it approaches the rear end. 45 The longitudinal edges —4—, and —5— of the barrel —1— are formed into recesses to receive the longitudinal edges —6— and —7— of the back-plate —8— which is partially punched to form a series, in this case 50 shown as sixteen, of spaced openings —9—

backed by enclosed baffles or plates —10— in angular relation to back-plate —8—.

The upper longitudinal edge of the back-plate —8— is formed to slidably fit into the upper longitudinal edge —5— of the barrel —1— forming in itself a recess —11— into which the upper edge of the adjusting plate —12— can slidably fit. The lower longitudinal edge —6— of back-plate —8— is similarly formed to slidably fit into the lower longitudinal edge of barrel —1—, and also to receive with a slidable fit the lower longitudinal edge of adjusting plate —12—, with the addition that this lower longitudinal edge of back-plate —8— is carried over and return bent to form a recess —13— into which the glass of the vehicle window —14— may be received and seated.

After the back-plate —8— is assembled into the barrel —1— it is preferable to lock 73 it in position by spot-welding or other convenient means.

The device is fashioned and assembled so that the baffles —10— extend inwardly towards the inside of the barrel —1— with their direction of angularity from the back-plate —8— towards the smaller or rear end —3— of the barrel —1—. It will be seen that the adjusting plate —12— being slidably mounted in the back-plate —8— permits a longitudinal adjustment of the device and permits adaptation to different widths of windows and a tight closure of the space in the window occupied by the device.

When the automobile or other vehicle carrying this device moves forward, the air through which the device is moving will enter the large end of the barrel —2— and be carried backward through the barrel, and will pass out through the small end —3— of the barrel at a greater or lesser velocity dependent on the speed of the car. This air passing through the device cannot enter the interior of the vehicle through the openings —9— because it will be deflected by the baffles —10—. It will, however, cause a draft or suction by aspiration which will draw air from the interior of the vehicle through the openings —9— into the barrel 100

—1— and out through the rear end —3— of the barrel.

The amount of air drawn from the interior of the vehicle will depend upon the quantity and velocity of the outside air being drawn 5 through the device.

The device is shown as removably secured in the wall of a vehicle, but it will be apparent that it may be permanently secured 10 in the wall of the vehicle as for instance, built in.

Altho I have shown and described a specific construction and form of part as illustrative of an embodiment of my invention, 15 I do not desire to restrict myself to the exact form, shape or arrangement of the parts, as various changes may be made within the scope of the appended claim.

I claim:

20 In a device of the class described, a plate having its central portion formed into an open sided cylinder, a second plate having a plurality of spaced apertures and having an outwardly extending baffle adjacent the edge 25 of each aperture, a recess formed on the top longitudinal edge of the first named plate for the reception of one longitudinal edge of the second named plate, a recess formed on the bottom longitudinal edge of the first 30 named plate for the reception of the other longitudinal edge of the second named plate and a glass receiving recess formed on the second-named plate adjacent the last named reception.

35 In witness whereof I have hereunto set my hand this 8th day of March, 1927.

EUGENE A. THOMPSON.
